UNITED STATES PATENT OFFICE.

EDGAR R. BULLARD, OF WHEELING, WEST VIRGINIA.

CAMERA.

SPECIFICATION forming part of Letters Patent No. 433,070, dated July 29, 1890.

Application filed January 17, 1890. Serial No. 337,164. (No model.)

To all whom it may concern:

Be it known that I, EDGAR R. BULLARD, a citizen of the United States, residing at Wheeling, in the county of Ohio and State 5 of West Virginia, have invented or discovered certain new and useful Improvements in Cameras, of which improvements the following is a specification.

The invention described herein relates to 10 certain improvements in that class of photographic cameras generally known as "detective - cameras." As heretofore constructed small cameras are of limited capacity.

The object of this invention is therefore to 15 provide a very compact camera with all the necessary conveniences and adjustments essential to a complete machine, including a direct and simplified focusing mechanism and a shutter having all the advantages of the rotary and drop shutters combined, being absolutely under the control of the operator, thereby admitting of any possible degree of 20 exposure, from time to instantaneous. The shutter is so constructed as to move transversely of and with the lens, having means 25 stationary relative to the lens for operating it.

In general terms the invention consists in the construction and combination of mechanical devices or elements, all as more fully hereinafter described and claimed.

In the accompanying drawings, forming a part of this specification, Figure 1 is a sectional elevation of my improved camera, the plane of section being indicated by the line 35 $x-x$, Fig. 1. Fig. 2 is an end elevation, the front end of the box or case being removed; and Fig. 3 is a perspective view of the shutter and its operating mechanism.

The case or box 1 is preferably made about 40 seven or eight inches long and four by four and one-half inches square, one part of its top side being hinged to the other part, forming a door 2 for the insertion and removal of the ground-glass screen and the plate-holder, and 45 in the front and rear ends are formed apertures, the one in the front end, for the exposure of the lens, being provided with a cap or plug 3, while the opening in the rear, formed so as to permit of inspection of the image on 50 the ground-glass screen, is preferably closed by a hinged door 4. The doors 2 and 4 are provided with suitable catches 5 and 6 for holding them in a closed position.

About midway of the case or box is formed a partition 7, having an opening therethrough, 55 and suitable springs 8 are provided in the rear of said partition for holding the ground-glass screen or the plate-holder firmly against the partition. At a suitable distance in front of the partition 7 is placed a second partition 9, having an aperture, and to the front side of said partition is attached one end of the bellows 10, the opposite end of said bellows being secured to a sliding block 12, around the edges of an opening 13, formed 60 through the block. This block is held against the bottom of the box or case by means of a screw 14, passing through the longitudinal slot 15 in the under side of the box and plate 17, the head of the screw engaging a spring 65 16, which slides along the plate 17, upon which is inscribed a table of distances, thereby making it an easy matter to focus the lens from the outside of the box or case without the employment of the ground glass. (See 70 Fig. 1.)

On the front face of the block 12 is fastened the ring or sleeve 18, forming a bearing for the lens-tube 19, which is slotted, as shown, for the passage of the curved plate 20 between 80 the lenses. At one end this plate is provided with a radial arm 21, which is pivotally attached to a plate 22, secured, as shown in Fig. 2, to the movable block 12. The center of curvature of the edges of the plate or shutter, 85 and also of the slot 23 formed therein, coincides with the pivot-pin connecting the arm 21 with the plate 22 or with the center of movement of the shutter.

The arm 21 is provided at its inner end with 90 a slotted toe 24, adapted to engage a pin 25, projecting through a vertical slot in the plate 22 and fastened to a vertically-movable rod 26. This rod, whose lower end projects through the under side of the box or case and 95 is provided with a suitable button, has a bearing in the under side of the box and also in an angle-plate 27, attached to one side of the box, as shown in Fig. 2, and is arranged approximately in line with the block 12 when 100 at the inner limit of its movement. The pin 25 is therefore made of sufficient length to remain in engagement with the toe 24 at every position of the block 12 and shutter 20. The upper end of the rod 26 is provided with a 105 rib or enlargement having teeth on its edge

with which a pawl 28 engages, so as to support the rod in its upper position. This pawl is secured to a horizontal rod 29, mounted in suitable bearings on the sides of the box and 5 provided with an arm 30, extending out horizontally or approximately so. An operating-rod 31 is attached to the free end of this arm and extends down through an opening in the under side of the box or case. By an upward 10 pressure on the button or head on the end of this rod 31 the rod 29 is rotated and the pawl disengaged from the toothed rod, with which the pawl is held in engagement by means of the downward pressure on rod 31 of the small 15 spring attached to the inside of the bottom of the box or case. On being released from the pawl 28, the weight of the rod 26 and shutter 20 causes the latter to drop to the position shown in Fig. 2, and in so dropping the slot 20 23 will admit light through the lenses onto the sensitive plate; but as this gravity movement is too slow to obtain a proper exposure under certain conditions, a rod 32 is flexibly connected at one end to one side of the box 25 or case, the opposite end passing loosely through a hole in the rib or enlargement on the rod 26, and to this rod is connected one end of a spring 33, the opposite end thereof being connected by a swivel-joint to a ten- 30 sion-screw 34, passing through a nut in the bottom of the case or box and terminating in a milled head 35. By properly adjusting the tension of the spring any desired rapidity of movement of the shutter may be attained. 35 Any other suitable means of connecting the spring and shutter may be employed; but that shown and described is preferred as being capable of exerting considerable force with but slight strain on the spring. The 40 downward movement of the shutter is arrested by a cushioning-stop 36, formed by a plate having an upturned portion and secured to the bottom of the case or box.

In using my camera the lens is focused by 45 shifting the block 12 by means of the projecting head of the screw 14 until the front edge of the spring-plate 16 (which, being attached to the screw 14, moves with it) coincides with the proper figures in the table of 50 distances inscribed on the metal plate 17, or until a properly-defined image is shown upon the ground-glass screen. The lens being properly adjusted, the shutter is set by pressing the rod 26 upward to its extreme limit, 55 when the pawl 28 will engage the lower tooth of the rib thereon, thereby holding the shutter with a solid portion in line with the lens. The slide is then withdrawn from the plate-holder, which has previously been placed in 60 position, the plug 3 removed, the camera properly directed at the object, and the exposure made by upward pressure on the rod 31, thereby disengaging the pawl and permitting the shutter to assume its lower position, as shown in Fig. 2, the slotted portion 65 23 having passed between the lenses in so doing. If, however, a time-exposure is desired,

the operator can, by means of the rod 26, either retard the movement of the shutter or entirely arrest its movement when the slotted portion thereof is in line with the lenses, as will be readily understood. If desired, a time or instantaneous exposure can also be effected by raising the shutter by upward pressure on the rod 26. 75

It will be readily understood that the case need not extend rearwardly much beyond the partition 7; but it is preferred to construct the case as shown, as the space behind the partition will contain a number of plate-holders where they can be readily carried. 80

I claim herein as my invention—

1. In a detective-camera, the combination of a box or case, an adjustable lens, a slotted shutter movable transversely of and with the 85 lens, and means stationary relative to the lens for operating the shutter, substantially as set forth.

2. In a detective-camera, the combination of an adjustable lens-tube, a curved slotted 90 plate arranged to move between the lenses and pivotally mounted at one side of the tube, and means stationary with relation to the tube for operating said shutter, substantially as set forth.

3. In a camera, the combination of a lens-tube, a curved and slotted plate arranged to move between the lenses and provided with a radial arm pivotally attached to a suitable support, a slotted toe attached to said arm, 100 and a longitudinally-movable rod provided with a pin engaging said slotted toe, substantially as set forth. 95

4. In a camera, the combination of a lens-tube, a curved and slotted plate arranged to 105 move between the lenses and provided with a radial arm pivotally attached to a suitable support, a slotted toe attached to said arm, a longitudinally-movable rod provided with a pin engaging said toe, a pawl arranged to 110 engage a tooth portion of the rod, and a rod for disengaging the pawl, substantially as set forth.

5. In a camera, the combination of a lens-tube, a curved and slotted plate arranged to 115 move between the lenses and provided with a radial arm pivotally mounted to a suitable support, a slotted toe attached to said arm, a longitudinally-movable rod provided with a pin engaging said toe, a pawl arranged to engage a tooth portion of said rod, a rod 31, connected to the pawl and operating the same, a horizontal rod pivoted at one end and engaging the vertically-movable rod 26 at the opposite end, and a spring for exerting a downward force on the horizontal rod, substantially as set forth. 120

In testimony whereof I have hereunto set my hand.

EDGAR R. BULLARD.
